FOLDED UMBRELLA

Robert Brooks, Great Neck, N.Y., assignor to The L. P.
Henryson Co., Inc., New York, N.Y.

Filed Dec. 2, 1970, Ser. No. 26,259

Term of patent 14 years

Int. Cl. D3—03

U.S. Cl. D88—3

FIG. 1 is a side elevation view of a folded umbrella showing my new design; the other sides not shown being substantially identical;

FIG. 2 is a top plan view of FIG. 1 on a larger scale; and

FIG. 3 is a bottom plan view of FIG. 1 on a larger scale.

The design is characterized by a strict frusto-conical configuration with an absence of protrusions from the wide ferrule end, said end being at least about twice as wide as the rib tip end.

I claim:

The ornamental design for a folded umbrella, substantially as shown and described.
